Primary Examiner — Clare E Heflin*(74) Attorney, Agent, or Firm* — Kilpatrick Townsend & Stockton LLP(57) **CLAIM**

The ornamental design for a light fixture, as shown and described.

DESCRIPTION

FIG. 1 is a top perspective view of a light fixture, showing our new design.

FIG. 2 is a left side view of the light fixture of FIG. 1.

FIG. 3 is a right side view of the light fixture of FIG. 1.

FIG. 4 is a rear view of the light fixture of FIG. 1.

FIG. 5 is a front view of the light fixture of FIG. 1.

FIG. 6 is a top plan view of the light fixture of FIG. 1.

FIG. 7 is a bottom plan view of the light fixture of FIG. 1; and, FIG. 8 is a bottom perspective view of the light fixture of FIG. 1.

Portions or features of the light fixture not shown in the drawings form no part of the claimed design. The broken lines in the drawings form no part of the claimed design.

1 Claim, 5 Drawing Sheets# US D670,856 S
